UNITED STATES PATENT OFFICE.

JOHN F. O'CONNOR, OF CHICAGO, ILLINOIS, ASSIGNOR TO WILLIAM H. MINER, OF CHAZY, NEW YORK.

ROLLER SIDE BEARING.

1,284,753.

Specification of Letters Patent. Patented Nov. 12, 1918.

Application filed March 30, 1917. Serial No. 158,491.

To all whom it may concern:

Be it known that I, JOHN F. O'CONNOR, a citizen of the United States, residing at Chicago, in the county of Cook and State 6 of Illinois, have invented a certain new and useful Improvement in Roller Side Bearings, of which the following is a full, clear, concise, and exact description, reference being had to the accompanying drawings, 10 forming a part of this specification.

This invention relates to improvements in roller side bearings.

The object of the invention is to provide a roller side bearing more particularly 15 adapted for use on railway cars and wherein is employed a roller in combination with spring means, the latter being so arranged as to return the roller to normal position after each actuation thereof.

20 In the drawing forming a part of this specification, Figure 1 is a vertical longitudinal section of a roller side bearing embodying my improvements. And Fig. 2 is a transverse section of the structure illustrated in Fig. 1, and taken on the line 2--2 thereof.

In said drawing, 10 denotes a portion of a truck bolster to which the improved roller side bearing, designated generally by the 30 reference A, is preferably attached, and 11 a portion of the body bolster of a car. As will be understood, a roller side bearing is interposed between the opposite ends of the truck and body bolsters in the usual manner.

35 The improved side bearing A, as shown, comprises a base casting 12 having lower flanges 13 by which it can be riveted or otherwise secured to the bolster and a hollow casing having side walls 113-113, 40 curved end walls 14-14, and a central upwardly extending transverse bearing portion or block 15. Mounted on the bearing 15 is the anti-friction roller 16, the same having a peripheral bearing surface 17 45 adapted to engage with the upper bolster 11 and a lower bearing surface 18 resting upon the bearing 15 of the base casting. Said bearing surfaces 17 and 18 are made concentric, with the bearing surface 18 of 50 shorter radius than that of the bearing surface 17. The normal position of the roller 16 is indicated in Fig. 1 and is automatically maintained in this position by spring means, the latter comprising two oppositely

arranged headed plungers 19 whose position 55 is controlled by springs 20. Each of the springs 20 is mounted in a diagonally extending recess 21 formed in the bearing 15 and each plunger 19 extends through its corresponding spring and through a guiding opening 22 at the bottom of the recess 21. The plungers 19 are prevented from accidental removal by any suitable means such as cotters 23. The heads of the plungers 19 engage shoulders 24-24 on the under sides of the roller 16 and, as clearly appears from Fig. 2, the plungers and corresponding springs are off-set with respect to each other. To prevent the roller 16 from falling out or becoming disengaged 70 from the casting 12, a pin 25 is extended therethrough, the ends of said pin working in elongated slots 26 formed in the side walls 113 of the casting 12. To prevent accidental displacement of the pin 25, washers 75 27 are applied and cotters 28.

The roller 16 is normally slightly spaced from the bolster 11 but when it comes into play, it is apparent that relative radial movement between the bolsters 11 and 10 80 will roll or rock the roller 16 to one side or the other of its normal position, and the dotted lines in Fig. 1 indicate the extreme movement to one side. To limit the amount of rocking or rolling movement, the curved 85 end walls 14 of the base casting are so located as to form stops to engage the roller, as clearly appears from Fig. 1 at the place indicated by the reference 29. As the roller is rocked or rotated from normal, it is apparent that one of the plungers 19 will be depressed against the action of its corresponding spring and the base casting is preferably recessed, as indicated at 30-30, to accommodate these movements of the 90 plunger. Upon removal of the pressure from the roller 16, it is obvious that the plunger which has been depressed will react under the influence of the spring and return the roller to normal position. The 100 side walls of the base casting may be recessed, as indicated at 31, to permit any dirt or other foreign matter to be readily washed out.

By employing the bearing surface 18 of 105 short radius, the bearing may be made of relatively short length while at the same time the roller 16 is placed under compres-

sion and bending strains on a journal are avoided, such as are incident to many types of roller side bearings.

I claim:

- 5 1. In a roller side bearing, the combination with a casting adapted to be secured to a bolster, said casting having a single centrally disposed transverse bearing, of a roller mounted on said bearing, the bearing surface of said roller engaging the top of said transverse bearing of the casting and being of less radius than the peripheral bearing surface of the roller, said roller thereby being placed under compression, and
10 15 means for returning said roller to normal position after each actuation thereof.
- 20 2. In a roller side bearing, the combination with a casting adapted to be secured to a bolster, said casting having a single centrally disposed transversely extending bearing, of a roller mounted on said casting, said roller having two concentric bearing surfaces of different radii, the bearing surface of shorter radius engaging the top of said
25 transverse bearing of the casting, to thereby place the roller under compression, and spring means mounted in the bearing of the casting adapted to return the roller to normal position after each actuation thereof.
- 30 3. In a roller side bearing, the combination with a casting adapted to be secured

to a bolster, said casting having a centrally disposed transversely extending bearing, of a roller mounted on said casting, said roller having two concentric bearing surfaces of 35 different radii, the bearing surface of shorter radius engaging the bearing surface of the casting, and spring means mounted in the bearing of the casting adapted to return the roller to normal position after each actuation 40 thereof, said spring means comprising oppositely arranged spring controlled plungers, the latter engaging the under side of the roller.

4. In a roller side bearing, the combination with a hollow base casting adapted to be secured to a bolster, the base casting having a transversely extending bearing therein, of a roller mounted on said bearing of the casting, means preventing accidental disengagement of the roller from the casting, the bearing of the casting having oppositely arranged recesses therein, springs in said recesses, and plungers controlled by said springs, said plungers normally engaging 55 the under side of the roller to maintain the latter in normal position.

In witness that I claim the foregoing I have hereunto subscribed my name this 15th day of March, 1917.

JOHN F. O'CONNOR.
